CLAIM

The ornamental design for a pipe connector, as shown (and described).

DESCRIPTION

FIG. 1 is a perspective view of a pipe connector showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front view for showing a pipe connected to the pipe connector;

FIG. 9 is a front view for showing the pipe connector to be further retracted; and,

FIG. 10 is a front view for showing another pipe connected to the pipe connector.

The broken line showing of pipe is included for the purpose of illustrating environmental structure and forms no part of the claimed design.
